UNITED STATES PATENT OFFICE.

JOHN T. TRUMBLE, OF FREEPORT, ILLINOIS.

TRANSMISSION MECHANISM FOR STARTERS.

1,256,746.

Specification of Letters Patent. Patented Feb. 19, 1918.

Application filed November 20, 1916. Serial No. 132,361.

To all whom it may concern:

Be it known that I, JOHN T. TRUMBLE, a citizen of the United States of America, residing at Freeport, in the county of Stevenson and State of Illinois, have invented certain new and useful Improvements in Transmission Mechanism for Starters, of which the following is a specification, reference being had therein to the accompanying drawings.

This invention relates to a mechanism adapted to couple a rotor and a driven or follower member and is especially adapted to couple a starter for an explosive engine with the latter, the action being automatic and the device being so disposed as to effect its purpose with a minimum number of parts and an action that avoids the liability to breakage or injury to either the starter or motor.

The invention consists in the matters hereinafter set forth, and more particularly pointed out in the appended claims.

In the drawings,

Figure 1 is a view, partially in elevation and partially broken away and in section, of a device that embodies features of the invention, shown in initial position; and

Fig. 2 is a similar view showing the device in engaged position.

As herein indicated, a starting motor 1 that may be of any approved type operates a drive shaft 2, the outer end portion of which may be supported in a suitable bearing 3, and the intermediate portion of which either carries or has formed thereon a worm thread or screw 4 of comparatively coarse pitch.

A bushing 5 is engaged by the worm so as to run easily and freely thereon. A friction sleeve 6 is non-rotatably and longitudinally reciprocable on the bushing 5, spline 7 or like means preventing inter-rotation of the parts and a spring 8 that encircles the bushing being in adjustable compression between the sleeve 6 and a tension nut 9 screwthreaded on to the bushing. A flange stop 10 limits the movement of the sleeve 6.

The face of the sleeve 6, which is slightly beveled and may have a renewable friction lining 11 of suitable material, is adapted to be brought into engagement with the peripheral surface 12 of the engine fly-wheel or like rotatable part of the motor to which the starter is to be connected, by suitable

disposition of the shaft 2 in relation to the axis of rotation of the rotatable member, the periphery 12 being beveled to correspond to the face of the sleeve 6. The parts are also so disposed that when at rest and not in contact with the face 12, the spring holds the sleeve against the stop 10.

In operation, the inertia of the bushing causes the initial rotation of the starter to turn the worm without rotating the bushing, and the latter moves along the worm until the sleeve is brought into contact with the engine wheel. This further momentarily locks the sleeve from rotation and holds it from shifting, while the bushing travels along the worm to a point where the resultant compression of the spring imposes sufficient end thrust to cause the parts to rotate in unison. They may even assume the position shown in Fig. 2 with the bushing contacting with the stop flange. Thus a firm, frictional engagement is had with the yielding and cushioning effect of the spring accommodating slight irregularities and safeguarding against sudden shock. When the motor picks up and overruns the starter, the sleeve and bushing are given a retrograde movement on the worm, drawing clear of the driven member and returning to initial position.

Thus a driving mechanism is obtained that acts automatically to maintain the proper driving and idling relations between the rotor and follower member. It is particularly effective between a starter and the motor which it operates, the automatic engagement and release making it peculiarly adaptable for such use.

Obviously, changes in the details of construction may be made without departing from the spirit of my invention and I do not care to limit myself to any particular form or arrangement of parts.

What I claim is:—

1. A coupling mechanism comprising a positively driven member, a follower member, a member for frictional engagement with the follower member rotatably and longitudinally shiftable on the positively driven member, and means for yieldingly holding such friction member in contact with a follower member and in non-rotatable engagement with the driving member when in such contact, the connection between the positively driven member and frictional engaging member causing the latter to shift on the

positively driven member until arrested from such movement by frictional engagement with a follower member.

2. The combination with a follower member, of a positively rotated driving member, and means for frictionally engaging the follower member that is rotatable and longitudinally reciprocable on the driving member, the engagement between the driving member and friction engaging means being such that inertia of the latter prevents rotation thereof relative to the driving member and causes axial movement along the latter into contact with the follower member, and means yieldingly holding the frictional engaging means both in contact with the follower member and in non-rotatable engagement with the driving member when in contact with the follower member.
- 20 3. The combination with a follower member, of a positively rotated driving member, means for frictionally engaging the follower member in screwthreaded engagement on the driving member, and means on the frictional means for yieldingly holding the latter in contact with the follower member, and a non-rotatable engagement with the driving member when in such contact, the inertia of the frictional engaging means preventing 30 rotation of the frictional member on the driving member until it contacts with the follower member.

4. The combination with a follower member, of a positively rotated driving shaft, a worm thereon, a bushing in screwthreaded engagement with the worm, a sleeve non-rotatable and axially reciprocable on the bushing, and means for yieldingly forcing the sleeve into contact with the follower 40 member when the inertia of the bushing causes the latter to shift along the worm when the latter is operated.

5. The combination with a follower member, of a positively rotated worm, a bushing 45 loosely screwthreaded on the worm, a sleeve non-rotatable and axially reciprocable on the bushing, a spring encircling the bushing and yieldably forcing the sleeve in one direction, the inertia of the bushing causing the latter to shift, the initial rotation of the 50 worm with the follower member and the spring operating to hold the sleeve in yielding engagement with the follower member and the bushing in engagement with the 55 worm when the sleeve is operated.

6. The combination with a follower member, of a positively rotatable driven member in parallel relation thereto, a worm on the

driving member, a bushing in screwthreaded engagement with the worm, a sleeve non-rotatable and axially reciprocable on the bushing provided with a face adapted to contact with the face of the follower member, a spring encircling the bushing and abutting the sleeve, and a nut on the bushing acting as a stop for the spring, the bushing being adapted to shift along the worm when the latter is rotated until the sleeve contacts with the follower member, and the spring being adapted to retain the bushing in non-rotatable engagement with the worm when the sleeve is in frictional engagement with the follower member.

7. The combination with a starter and an explosive engine, having a rotatable member adapted to turn the engine and be turned thereby, of a worm positively driven by the starter, a bushing in screwthreaded and rotatable engagement on the worm, a sleeve longitudinally reciprocable on the bushing 80 adapted to engage frictionally on the rotatable member of the engine, a thrust nut adjustably mounted on the bushing, and a spring in compression between the thrust nut and the sleeve, the bushing being adapted to be shifted along the worm when the latter is initially rotated because of the inertia of the bushing and the spring operating to force the sleeve into rotatable engagement with the rotating member of the engine, and simultaneously therewith to lock the bushing to turn with the worm.

8. The combination with an explosive engine having a rotating member that is positively connected to the engine to drive and 95 be driven by the latter, of a starter having a worm that is positively driven thereby, a bushing loosely screwthreaded on the worm, the inertia of which causes the bushing to shift along the worm until arrested, a sleeve 100 non-rotatable and longitudinally shiftable on the bushing, a thrust nut adjustably secured on the bushing, and a spring in compression between the thrust nut and sleeve adapted to maintain the latter in yielding 105 contact with the rotatable member of the motor when the bushing shifts into operative relation to the latter and simultaneously therewith to hold the bushing in non-rotatable engagement with the worm.

In testimony whereof I affix my signature in presence of two witnesses.

JOHN T. TRUMBLE.
